RUDOLPH A. RIEK, OF RHINELANDER, WISCONSIN

HOOD COVER

Application filed January 18, 1927. Serial No. 161,849.

This invention relates to a cover designed for use in connection with the hood of an automobile, one of the objects being to provide an efficient cover utilizing the minimum amount of material in its construction and which is so designed as to leave exposed the greater portion of the hood so that it will not be marred by long contact, while in a heated condition, with the inner surface of the cover. 5 Hood covers as generally constructed extend entirely over the hood, concealing the louvers at the sides thereof. It has been found in practice, however, that for the purpose of protecting the radiator it is not essential that 10 the louvers be entirely covered. It has also been found undesirable to have the cover completely concealing the hood because it tends to remove the gloss from the finish through constant friction thereon and be- 15 cause of the retention of excessive heat. Moreover it has been thought necessary to extend a cover entirely over a hood in order to properly fasten it in position. It has been found, however, that such a construction is 20 not essential and one of the objects of the present invention is to provide a cover which can be produced much more cheaply than heretofore, leaves the top of the hood exposed, allows the heated air and gases to escape 25 through certain of the louvers, and permits attachment of the hood cover in the usual way.

A further object is to provide the cover with an adjustable apron for controlling the 30 flow of cold air through the radiator.

Another object is to provide a cover which is attractive in appearance and tends to add to the beauty of the vehicle rather than detract therefrom.

With the foregoing and other objects in view which will appear as the description proceeds, the invention resides in the combination and arrangement of parts and in the details of construction hereinafter de- 40 scribed and claimed, it being understood that changes in the precise embodiment of the invention herein disclosed may be made within the scope of what is claimed, without departing from the spirit of the invention.

In the accompanying drawings the pre-

ferred form of the invention has been shown.

In said drawings,

Figure 1 is a side elevation of the radiator and hood of an automobile showing the cover applied thereto, a portion of the cover being 55 in section.

Figure 2 is a front elevation of the cover applied to a radiator.

Figure 3 is a section through the cover on line 3—3, Figure 2.

Referring to the figures by characters of reference 1 designates the front of the cover, the same being formed of a suitable fabric so shaped as to conform with the contour of a radiator R, and being preferably of such length as to hang below the radiator as shown at 2. An opening 3 is formed in the front of the cover and secured to said front adjacent the bottom of the opening is a curtain 4 provided along its side edges and top with 70 snap fasteners 5 or the like whereby the curtain can be held flat upon the front of the cover and completely close the opening 3. Should it be desired to partly expose the opening, however, the fasteners can be detached, 75 the curtain lowered, and the members of the fasteners pressed together so as to support the curtain as shown for example in Figure 1. Obviously by having the fasteners spaced apart at regular intervals the size of the exposed portion of the opening and, consequent- 80 ly, the area of the exposed portion of the radiator can be varied at will. Extending backwardly from the front 1 of the cover are side wings 6 formed of the same kind of 85 material as the front and having apertures 7 near their lower edges for the reception of the hood fasteners F. The upper edges of the wings 6 curve upwardly and forwardly and merge at the top of the hood close to the radiator, the top portion of the cover being suf- 90 ficiently broad to permit the formation of an opening 8 therein for the reception of the filling sleeve S projecting upwardly from the radiator. It will be noted that when the cover is in position practically the entire top of the hood is exposed and only portions of the louvers L are concealed. Consequently 95 the objections due to the use of a cover that extends entirely over the hood are avoided 100

and a portion of the heated air is permitted to escape so that the hood will not become overheated.

In addition to the advantages already set forth, the present invention is desirable because it permits the engine to be more readily inspected than where a cover is extended entirely over the hood. In other words, if an inspection of the engine is desired, one side of the cover can be detached and folded back, thus allowing one side of the hood to be raised. Furthermore if necessary both wings of the cover can be detached and swung back without removing the front portion of the cover from the radiator. Thus both sides of the hood can be opened easily.

What is claimed is:

A hood cover including a front portion adapted to extend across and around a radiator, and wings extending from the sides of said front portion having their upper edges inclined downwardly and rearwardly from the top of the radiator engaging portion of the cover and integral therewith, either of said wings being foldable forwardly to permit raising one side of the hood to which the cover is connected.

In testimony that I claim the foregoing as my own, I have hereto affixed my signature.

30 EMIL LEHMANN.
